UNITED STATES PATENT OFFICE.

AUGUST J. WOHLPART, OF NEW YORK, N. Y., ASSIGNOR TO UNION SPECIAL MACHINE COMPANY, OF CHICAGO, ILLINOIS, A CORPORATION OF ILLINOIS.

FEEDING MECHANISM FOR SEWING-MACHINES.

1,384,797.

Specification of Letters Patent. Patented July 19, 1921.

Application filed January 7, 1915. Serial No. 944.

To all whom it may concern:

Be it known that I, AUGUST J. WOHLPART, a citizen of the United States, residing at New York, in the county of New York, 5 State of New York, have invented certain new and useful Improvements in Feeding Mechanism for Sewing-Machines, of which the following is a description, reference being had to the accompanying drawing and 10 to the figures of reference marked thereon.

The invention relates to new and useful improvements in feeding mechanisms for sewing machines, and more particularly to a feeding mechanism for a sewing machine 15 having a work-supporting arm in which the feeding mechanism is located, and consists of main and auxiliary feed dogs which may be given a differential movement relative to each other during the feeding of the 20 material.

An object of the invention is to provide a feeding mechanism of the above character with means for varying the differential movement of the feed dogs relative to each other, 25 or for causing said feed dogs to move in unison, which means may be controlled by the operator without stopping the stitching mechanism.

A further object of the invention is to 30 provide a feeding mechanism of the above character with means for supporting the auxiliary feed dog, whereby the position of said feed dog relative to the surface of the work-supporting arm may be adjusted.

These and other objects will in part be 35 obvious, and will in part be hereinafter more fully described.

In the drawings which show by way of 40 illustration one embodiment of the invention,

Figure 1 is a side elevation with parts broken away and parts in section, showing a machine embodying my improvements;

Fig. 2 is a view partly in top plan and 45 partly in horizontal section, showing a portion of the feeding mechanism and the devices for regulating the same;

Fig. 3 is an enlarged view partly in side elevation and partly in section, showing the 50 controlling means for varying the throw of the feed dogs;

Fig. 4 is a similar view showing the controlling means shifted to a different position;

Fig. 5 is a detail partly in section and

partly in end elevation, showing the controlling means and the position of the same relative to the standard of the machine. 55

Fig. 6 is a detail on a small scale, showing the treadle connection for shifting the controlling lever; 60

Fig. 7 is an enlarged detail in section, showing the two feed dogs and the manner or supporting the same.

Fig. 8 is an end view of the same. 65
The invention consists generally in providing a sewing machine having a standard and a work-supporting arm with a feeding mechanism which is located in said work-supporting arm. Said feeding mechanism includes a main feed dog and an auxiliary 70 feed dog. The auxiliary feed dog is operated through the mechanism which reciprocates the main feed dog by intermediate devices which may give to the auxiliary feed dog a differential movement relative to the 75 main feed dog. These devices may be adjusted so the two feed dogs will move in unison. These intermediate devices which give the differential throw to the auxiliary feed dog, may be manually shifted for varying the throw or for causing said auxiliary feed dog to move in unison with the main feed dog. This manual control may be effected without stopping the stitching mechanism. 80

Referring more in detail to the drawings, I have shown my improved feeding mechanism as embodied in a sewing machine consisting of a standard 1, on which is mounted an overhanging arm 2. A needle bar 3 reciprocates in said overhanging arm and carries needles 4, 4. The needle bar is reciprocated by the usual needle lever from an eccentric on the main shaft 5. This main shaft extends crosswise of the standard. This needle-operated mechanism is of the well known construction in this type of machine. 85

Also carried by the standard 1 is a work-supporting arm 6, preferably cylindrical in 90 shape. Mounted in the work-supporting arm is a looper shaft 7 carrying a looper 8, which cooperates with the needles 4, 4. The material is held upon the work-supporting arm by a presser foot 9, carried by a presser 95 bar 10. This machine is particularly adapted for stitching tubular articles, and the articles to be stitched are fed lengthwise of 100

the work-supporting arm. This feeding mechanism consists of a main feed dog 11 and an auxiliary feed dog 12.

Extending lengthwise from the arm is a main feed bar 13. The main feed bar 13 at its rear end is provided with a slotted bracket 14, which engages the pin 15 carried by the feed rocker 16. Said slotted end is adapted to slide back and forth on said pin. The feed rocker 16 is mounted on a cross shaft 17, and carries an arm 18 connected to a link 19 coöperating with an eccentric on the main shaft 5. As this main shaft 5 rotates, the arm 18 will be oscillated, and this in turn will vibrate the feed rocker back and forth. Said feed rocker carries a slotted bracket 20. A link 21 is adjustably connected to said slotted bracket at one end, and at its other end is pivotally attached to the feed bar 13. As this feed rocker moves back and forth, the link 21 will cause the feed bar to reciprocate lengthwise in said work-supporting arm.

The feed bar adjacent the main feed dog 25 is in the form of a shaft, and on this shaft is a sleeve 22, which sleeve carries the auxiliary feed dog. At the forward end of the sleeve 22 is a bracket 23, and the auxiliary feed dog, (which as herein shown is in three sections,) is adjustably attached to this bracket by suitable screws 24. By loosening the screws 24, the auxiliary feed dog may be raised and lowered and the position of the same relative to the surface of 35 the work-supporting arm varied.

A lever 25 extends lengthwise of the work-supporting arm and is fulcrumed at 26 on a bracket carried by said arm. At the forward end of said lever, there is a link 27, 40 which link at its upper end is pivoted to the sleeve 22 carrying the auxiliary feed dog. The lever 25 extends rearwardly into the standard, and is pivotally connected to a link 28, which coöperates with an eccentric 45 29 on the main shaft 5. As the main shaft 5 rotates, this eccentric will oscillate the lever 25, raising and lowering the front end of the same, which in turn raises and lowers the sleeve 22 and the feed bar which 50 extends through the same. This gives the up and down movements to both feed dogs. While the sleeve 22 moves up and down with the feed bar 13, it is free to move endwise on said feed bar.

55 Pivoted to the feed bar at 30 is an auxiliary feed rocker 31. This auxiliary feed rocker 31 has a rearwardly extending arm 32 which is pivotally connected to a link 33. The link 33 at its lower end is attached 60 to an arm 34, fixed to the cross shaft 17, carrying the main feed rocker 16. As this main feed rocker oscillates, the arm 34 is moved up and down and through the link 33 will rock the auxiliary feed rocker 31. 65 Said auxiliary feed rocker 31 is provided

with a second arm 35, extending downwardly from the fulcrum of the feed rocker and formed with a slot 36.

A link 37 is pivoted at one end to a stud 35^a which is adjustable up and down in the slot 36, while the other end of this link is pivoted at 38 to the sleeve 22. This stud 35^a may be moved over the fulcrum point 30 of the auxiliary feed rocker, as shown in Fig. 4, and when so positioned the oscillating movements of the auxiliary feed rocker will have no effect upon the link 37.

The pivot stud 35^a may be shifted along the slot to any desired position, or to the lower end of the slot, as shown in Figs. 1 80 and 3, and when in this position, the oscillations of the auxiliary feed rocker through the link 37 will cause the sleeve 22 to move endwise on the feed bar 13. It is to be noted that this auxiliary feed rocker is pivoted 85 on the main feed bar, and, therefore, bodily moves back and forth with the feed bar in addition to the oscillating movements imparted to the auxiliary feed rocker through the link 33. The feeding mechanism above 90 described *per se* forms no part of my present invention, except as it embodies a differential feeding mechanism which may be controlled by the mechanism hereinafter described.

The link 37, which gives to the sleeve 22 95 its movements relative to the main feed bar, may be shifted so that this throw of the sleeve 22 relative to the main feed bar may be varied, by means of a lever 39, which is freely pivoted on the cross shaft 17. This 100 lever is connected by a link 40 to the link 37. The lever at the rear end is connected to a rock lever 41 by a link 42. The rock lever 41 is pivoted at 43 to the standard 1 105 of the machine.

A spring 44 is attached to one arm of the rock lever 41 at one end, and to a suitable lug 45 on the standard at its other end. This spring normally shifts the rock lever 41, so as to depress the rear end of the lever 39, 110 and this through the link 40 will raise the link 37 to neutral position, that is, with the pivot stud 35^a over the fulcrum of the auxiliary feed rocker. The rock lever 41 may be moved in the opposite direction by a chain 115 46, which may be connected to a treadle 47, see Fig. 6.

In order to limit the movements of the rock lever 41, I have provided said rock lever with two spaced arms 48 and 49, each 120 of which is provided with an adjustable screw 50. A pin 51 carried by the standard of the machine, serves as an abutment for these stops and limits the movements of the rock lever 41.

125 From the above description, it will be apparent that I have provided a feeding mechanism wherein a main feed bar carries a main feed dog, and said main feed bar is reciprocated back and forth longitudinally 130

of a work-supporting arm. An auxiliary feed dog, is also moved back and forth longitudinally of the work-supporting arm, by devices which are intermediate the main 5 feed rocker and the auxiliary feed dog, which devices may be so shifted that the auxiliary feed dog will move in unison with the main feed dog, that is, the auxiliary feed dog and the main feed dog at each feeding 10 action will feed the material equal distances, or may be given a differential movement relative to said main feed dog, that is, the auxiliary feed dog will move the fabric a little faster than the main feed dog.

15 Furthermore, this differential feeding movement imparted to the auxiliary feed dog may be varied by depressing the treadle. When the treadle is depressed, the auxiliary feed dog will be given a differential feeding 20 movement. When the treadle is released, the spring 44 will shift the rock lever 41 to the position shown in Fig. 4, and then said auxiliary feed dog will move in unison with the main feed dog. This shifting or controlling 25 of the movements of the auxiliary feed dog may be quickly accomplished, without stopping the stitching mechanism. It is noted that the treadle controlled lever is mounted on the standard and not on the 30 work supporting arm, and, therefore, the work supporting arm is left entirely free to receive the garment.

The auxiliary feed dog is located in front of the needles and engages the material and 35 feeds the same to the needles, while the main feed dog is located substantially in rear of the needles. This machine is particularly adapted for stitching elastic material and when operating upon such material, the 40 auxiliary feed dog may be given a slightly faster feeding movement than the main feed dog, thus crowding the elastic material to the needles to prevent the stretching of the same.

It is obvious that minor changes in the 45 construction and arrangement of the parts may be made, without departing from the spirit of the invention, as set forth in the appended claims.

Having thus described my invention, 50 what I claim as new and desire to secure by Letters Patent, is:—

1. In a sewing machine, the combination of a standard, a work-supporting arm projecting therefrom and a feeding mechanism 55 located within said work-supporting arm for feeding the material longitudinally thereof, said feeding mechanism including a main feed bar, a feed dog carried thereby, a sleeve embracing said main feed bar and capable 60 of endwise movement thereon, an auxiliary feed dog carried by said sleeve, means for moving said sleeve endwise in unison with the main feed bar or for giving a differential movement to said sleeve, means under the 65 control of the operator for giving to said

sleeve said differential movement or for causing the same to move in unison with the main feed bar, said last named means including a lever located in said work-supporting arm, a rock lever pivoted to said standard and connected to said lever, and a manually-operated member connected to said rock lever.

2. In a sewing machine, the combination of a standard, a work-supporting arm projecting therefrom and a feeding mechanism located within said work-supporting arm for feeding the material longitudinally thereof, said feeding mechanism including a main feed bar, a feed dog carried thereby, a sleeve 75 embracing said main feed bar and capable of endwise movement thereon, an auxiliary feed dog carried by said sleeve, means for moving said sleeve endwise in unison with the main feed bar or for giving a differential movement to said sleeve, means under the control of the operator for giving to said sleeve said differential movement or for causing the same to move in unison with the main feed bar, said last named means including a lever 80 located in said work-supporting arm, a rock lever pivoted to said standard and connected to said lever, a manually-operated member connected to said rock lever, spaced stops 85 carried by said rock shaft and an abutment 90 carried by said standard with which said stops coöperate.

3. In a sewing machine, the combination of a standard, a work-supporting arm projecting therefrom and a feeding mechanism 100 located within said work-supporting arm for feeding the material longitudinally thereof, said feeding mechanism including a main feed bar, a feed dog carried thereby, a sleeve 105 embracing said main feed bar and capable of endwise movement thereon, an auxiliary feed dog carried by said sleeve, means for moving said sleeve endwise in unison with the main feed bar or for giving a differential movement to said sleeve, means under the 110 control of the operator for giving to said sleeve said differential movement or for causing the same to move in unison with the main feed bar, said last named means including a lever located in said work-supporting arm, a rock lever pivoted to said standard and connected to said lever, a spring for moving 115 said rock lever in one direction and a treadle for moving the rock lever in the other direction, and stops for limiting the movement of the rock lever in each direction.

4. In a sewing machine, the combination of a standard, a work-supporting arm projecting therefrom and a feeding mechanism located within said work-supporting arm for 120 feeding the material longitudinally thereof, said feeding mechanism including a main feed bar, a feed dog carried thereby, a sleeve 125 embracing said main feed bar and capable of endwise movement thereon, an auxiliary 130

- feed dog carried by said sleeve, means for moving said sleeve endwise in unison with the main feed bar or for giving a differential movement to said sleeve, means under 5 the control of the operator for giving to said sleeve said differential movement or for causing the same to move in unison with the main feed bar, said last named means including a lever located in said work-supporting arm, a rock lever pivoted to said standard and connected to said lever, a spring for moving said rock lever in one direction and a treadle for moving the rock lever in the other direction, spaced adjustable screws carried by said rock lever, and an abutment mounted on said standard with which said screws coöperate for limiting the movement of said rock lever in each direction.
- 20 5. In a sewing machine, the combination of a standard, a work-supporting arm projecting therefrom, a feeding mechanism located in said work-supporting arm for feeding the material longitudinally of said arm and including a main feed bar, a feed dog carried thereby, an auxiliary feed bar and a feed dog carried thereby, a feed rocker for said main feed bar for moving the same endwise in said arm, an auxiliary feed rocker 25 mounted on said main feed bar, means for oscillating said auxiliary feed rocker from said main feed rocker, said auxiliary feed rocker having a slotted arm, a link for connecting said slotted arm to the auxiliary feed bar, said link being shiftable along said slot for varying the throw imparted to said auxiliary feed bar or for causing said auxiliary feed bar to move in unison with the main feed bar, and means under the control of the operator for shifting said link connection with the auxiliary feed rocker without stopping the stitching mechanism, including a lever located in said work-supporting arm and projecting into the standard, a link connecting the end of the lever with said link for connecting said slotted arm to the auxiliary feed bar, and means whereby said lever may be shifted by the operator.
6. In a sewing machine, the combination 50 of a standard, a work-supporting arm projecting therefrom, a feeding mechanism located in said work-supporting arm for feeding the material longitudinally of said arm and including a main feed bar, a feed dog carried thereby, an auxiliary feed bar and a feed dog carried thereby, a feed rocker for said main feed bar for moving the same endwise in said arm, an auxiliary feed rocker mounted on said main feed bar, means for oscillating said auxiliary feed rocker from said main feed rocker, said auxiliary feed rocker having a slotted arm, a link for connecting said slotted arm to the auxiliary feed bar, said link being shiftable along said slot for varying the throw imparted to said

auxiliary feed bar or for causing said auxiliary feed bar to move in unison with the main feed bar, means under the control of the operator for shifting said link connection with the auxiliary feed rocker without stopping the stitching mechanism, including a lever located in said work-supporting arm and projecting into the standard, a link connecting the end of the lever with said link which operates the auxiliary feed bar, a rock lever mounted on said standard, a link connecting one arm of said rock lever to said lever, a treadle connected to the other end of said rock lever, a spring for moving the rock lever in one direction, and stops for limiting the movement of the rock lever in each direction.

7. A sewing machine including in combination a standard, a horizontal work supporting arm carried by and projecting from said standard, a feeding mechanism comprising a main feed supporting member extending longitudinally of and located within said work supporting arm, a main feed dog carried thereby, an auxiliary feed supporting member located within said work supporting arm, an auxiliary feed dog carried thereby, means for raising and lowering said feed dog supporting members, means for moving said main feed dog supporting member back and forth, means for moving said auxiliary feed dog supporting member back and forth and for giving thereto a differential movement relative to the main feed dog, and means under the control of the operator for varying the differential movement given to the auxiliary feed dog whereby said auxiliary feed dog may be caused to move in unison with the main feed dog and without stopping the stitching mechanism, said last-named means including a lever located within said work supporting arm, a rock lever pivoted to the standard and connected to said first-named lever, and a manually operated lever connected to said rock lever.

8. A sewing machine including in combination, a standard, a horizontal work supporting arm carried by and projecting from said standard, a feeding mechanism comprising a main feed supporting member extending longitudinally of and located within said work supporting arm, a main feed dog carried thereby, an auxiliary feed supporting member located within said work supporting arm, an auxiliary feed dog carried thereby, means for raising and lowering said feed dog supporting members, means for moving said main feed dog supporting member back and forth, means for moving said auxiliary feed dog supporting member back and forth and for giving thereto a differential movement relative to the main feed dog, and means under the control of the operator for varying the differential move-

ment given to the auxiliary feed dog whereby said auxiliary feed dog may be caused to move in unison with the main feed dog and without stopping the stitching mechanism, said last-named means including a lever located within said work supporting arm, a rock lever pivoted to the standard and connected to said first-named lever, a manually operated lever connected 10 to said rock lever, spaced stops carried by

the rock lever, and an abutment mounted on the standard with which said stops cooperate.

In testimony whereof, I affix my signature in the presence of two witnesses.

AUGUST J. WOHLPART.
